UNITED STATES PATENT OFFICE.

NORMAN ISACHSON, OF ALBION, IDAHO.

ADDITIONAL AIR-SUPPLY FOR EXPLOSIVE-ENGINES.

1,130,293.

Specification of Letters Patent.

Patented Mar. 2, 1915.

Application filed August 4, 1914. Serial No. 854,998.

To all whom it may concern:

Be it known that I, NORMAN ISACHSON, a citizen of the United States, residing at Albion, Idaho, have invented certain new and useful Improvements in Additional Air-Supply for Explosive-Engines, of which the following is a specification.

This invention relates to an auxiliary air supply for internal combustion engines and the invention in general is in supplying additional air to the explosive charge after it has left the carburetor and before it reaches the cylinders proper of the engine. I supplement my auxiliary supply with a priming device.

The invention consists in the features of construction and arrangements and combination of parts hereinafter described and particularly pointed out in the claims, it being understood that I do not wish to limit myself to the details of the different parts of my invention.

The invention is illustrated in the accompanying drawings in which:

Figure 1 is a side elevation of the auxiliary air supply showing an ordinary attachment of it to an automobile; Fig. 2, is a side elevation of the air valve on the steering column; Fig. 3, is a sectional side view of the valve and Fig. 4, is a sectional plan view.

In the drawing the numeral 1 indicates a steering column of an automobile and 2 the steering wheel thereon.

3 indicates the dashboard.

4 indicates the manifold of the engine and 5 a carburetor. Connected to the manifold at some point between the carburetor and the engine preferably at 6, is a pipe 7 which runs, by means of suitable joints and connections 8 and 9, up along the steering column 1 until it terminates in an air valve 10, in such proximity to the steering wheel that its handle 11 may be easily operated by the driver of the automobile without removing his hand from the steering wheel. At some point in this pipe 7, preferably under the hood or bonnet is located what I call a signal oil feed cup, an article that is well known on the market and is used ordinarily as a lubricator. However, I use this cup to hold gasoline so that when it is desired to prime the engine, the driver only has to raise the handle 12 thereon to allow liquid gasoline to run down the pipe 7 therefrom into the manifold of the engine where-

by the latter may be more easily started. Whenever it is desired to clean out the cylinders of the engine, kerosene or some other carbon solvent may be put into the oil feed cup and allowed to run down into the engine. At some convenient point between this cup for gasoline and the manifold I provide a strainer 13 adapted to strain both gasoline and air. As a further aid to starting the engine I may employ a torch around the vertical part 14 of the manifold which consists simply in an annular ring or basin 15, in which gasoline or alcohol may be burned to heat the horizontal portion 4 of the manifold to make the charge more easily gasifiable.

Referring now to Figs. 2 to 4 illustrating the air valve 10; the valve consists of an inner cup shaped member 15 having an elongated bottom with an opening therein. On this elongation are arranged nut faces 16 on which a wrench may fit and screw threads 17 below it whereby the device may be attached to the pipe 7. The outer member or closure 18 of the device has secured to it a handle 11. This closure has a plurality of openings or gates 19 of particular shape and of varying position in the closure. These openings are substantially rectangular in shape having a small slot 20 extending upward therefrom. The small slots 20 are to permit a much finer adjustment of the air intake than the rectangular openings alone would allow. There are preferably four of these openings which are unequally distanced from the top of the closure 18, each succeeding one being nearer the top, and in the same manner the slots 20 are of an increasing height so that each succeeding one extends nearer the top of the closure 18. The lower member 15 has screw threads 21 in its interior that are very sharply pitched. I have found two threads to be sufficient, each thread making a turn of only about two hundred degrees. Depending centrally from the top of the closure 18, is a hollow tube 22 which carries a plurality of flat fingers 23 so spaced from each other and with their extremities so inclined as to engage between them the threads 21 on the interior of the cup shaped member 16. A pin 23 extends entirely through the device passing through the hollow tube 22, carrying nuts 25 at its upper end and a rivet 26 at its lower end, which pin serves to hold the two parts 16 and 18 together.

In operation the air valve 10 is normally closed. When it is desired to start the engine it may be primed by means of my priming device which only requires the lifting of the handle 12 to allow liquid gasoline to run directly into the manifold. As a further aid in starting the torch 15 may be lighted to heat the manifold. Then when the engine is running and driving the automobile the air valve may be brought into operation. When a gasoline engine gets warmed up and running fast, it is known that considerable air may be added to the mixture without decreasing the efficiency of the motor, and it can be readily seen that to do this would be to save fuel. This is what the air valve is to do. With the openings 19 differently spaced from the top of the closure 18 of the valve and with their slots 20 of different heights, a very fine adjustment of the amount of additional air can be obtained. As the closure 18 is rotated by means of the handle 11, the threads 21 acting upon the fingers 23 of the closure, cause it to rise and in rising above the edge of the inner member 16 admit an increasing amount of air by means of the differently disposed openings. After the closure 18 has risen to this extent, such an amount of air is admitted as to be more than enough for the explosive mixture but this is for the purpose of so diluting the mixture that there will be no explosion in the engine as is desirable when going down hill. In this way the engine may be used as a brake under these conditions besides being cooled at the same time by the non-explosive mix-

ture that is passing through it. The closure 18 is so nicely fitted upon the member 16 that when the closure 18 is screwed down in its lowermost position, no air whatever can enter the air openings. 40

I claim as my invention:

1. A system of auxiliary air supply for internal combustion engines comprising an air conducting pipe attached to the manifold 45 between the carburetor and the engine, and means for admitting an increasing amount of air to said pipe comprising a cup shape member on said pipe and a rotatable closure over said cup shape member having openings of successively increasing area therein 50 differently distanced from the top thereof for the purpose of admitting an increasing amount of air to said pipe.

2. An auxiliary air valve for automobiles 55 comprising a cup shaped member having a closure therefor, openings therein of successively increasing area and differently distanced from the top, and means for rotating and elevating said closure to render said 60 openings operative comprising screw threads on the interior of the cup shaped member, a central pin extending through the valve, and wings having differently directioned ends carried by said pin and engaging said 65 threads.

In testimony whereof, I affix my signature in presence of two witnesses.

NORMAN ISACHSON.
